CLAIM

The ornamental design for a display screen or portion thereof with icon, as shown and described.

DESCRIPTION

The patent file contains at least one drawing executed in color. Copies of this patent with color drawing(s) will be provided by the Office upon request and payment of the necessary fee.

FIG. 1 shows a front view of a display screen or portion thereof with sensor icon; and,

FIG. 2 shows a front view of another embodiment thereof. The dash-dash broken lines in the figures are shown to indicate unclaimed portions of the sensor icon and form no part of the claimed design. The dot-dash broken lines illustrate a display screen or portion thereof and the boundary of the claimed design. The dot-dash broken lines form no part of the claimed design.

1 Claim, 2 Drawing Sheets
